UNITED STATES PATENT OFFICE.

ISAAC HARPER AND SAMUEL HARPER, OF PITTSBURG, PENNSYLVANIA.

REGENERATING-FURNACE.

SPECIFICATION forming part of Letters Patent No. 274,320, dated March 20, 1883.

Application filed October 16, 1882. (No model.)

To all whom it may concern:

Be it known that we, ISAAC HARPER, a citizen of England, (but having declared an intention of becoming a citizen of the United States,) and SAMUEL HARPER, a citizen of the United States, both residing at Pittsburg, county of Allegheny, State of Pennsylvania, have invented or discovered a new and useful Improvement in Regenerating-Furnaces; and we do hereby declare the following to be a full, clear, concise, and exact description thereof, reference being had to the accompanying drawings, making a part of this specification, in which—like letters indicating like parts—

15 Figure 1, Sheet 1, is a horizontal sectional view of our improved furnace, the planes of section being indicated by the broken line $x\ x$, Fig. 2. Fig. 2 is a vertical sectional view, the planes of section being indicated by the line $x'\ x'$, Fig. 1. Fig. 3, Sheet 2, is a transverse vertical section taken in the plane of the broken line $x^2\ x^2$, Fig. 2. Fig. 4 is a similar view of part of the air valve and passages, taken in the line $y\ y$, Fig. 2; and Fig. 5 is a similar view 25 of a portion of the gas-valve and passages, taken in the line $z\ z$, Fig. 2.

Our invention relates to certain improvements in regenerator-furnaces, and more particularly to those designed for steel-melting; 30 and it consists in the combination, with such a furnace, of a new and improved system of supply-flues leading to the regenerating-chambers, whereby a more uniform distribution of air and gas is secured throughout the furnace, 35 and difficulties are removed which have heretofore placed a comparatively low limit upon the size or capacity of such a furnace.

We have illustrated our invention as applied to or in combination with the regenerator of a 40 Siemens steel-melting furnace; but it may be applied in substantially the same way to regenerator-furnaces of other forms designed for other uses; and therefore we do not wish to limit our invention by the specific application 45 shown and described.

In the drawings we have illustrated a succession of eight steel-melting chambers, A, arranged in line and covered by arched caps A'. These chambers may be of the usual form 50 and construction, consisting of side walls, $a\ a$, bottom or hearth a' , and pulverized coke or

other suitable bed, a^2 , on which the pots or crucibles are set. Below these chambers is the usual ash-pit, A².

On either side of the line of melting-chambers A are built two regenerating-chambers, B B and C C—four in all—two, B B, being gas-chambers, and two, C C, air-chambers. These chambers are wholly or partially filled with the usual or any desired form of brick 55 checker-work, as represented at D, and they communicate with the melting-chambers by ports e, which open through the arches $b'\ c'$ into flues b, which latter lead over the chambers B C into the chambers A, as represented 60 in Figs. 2 and 3.

Underneath the chambers B C are distributing-flues E F, which extend the length of the chambers, are closed at their ends, and are open above directly into the chambers along their 65 whole length except at the center, where arches H are sprung over ports h, which afford communication between the distributing-flues and supply-flues I I'. These supply-flues are built under and in line with the distributing-flues 70 E F, and extend forward from the middle of the furnace to chambers or passages L L', (see 75 Figs. 4 and 5,) which communicate with the usual or any suitable gas and air valve mechanism R R', provided with regulating-valves r 80 r' and reversing-valves r². The mechanism for operating these valves may be of the usual construction, which is well known in the art, and need not be shown. Air may be admitted to either passage L' directly through the valve 85 r', and thence to either the right or left hand supply-flue I', depending upon the position of reversing-valve r². Also, gas may be admitted in like manner to either flue I I through trunk S, which leads from any suitable generator. 90 The passages s underneath the reversing-valves r² open into a flue, S', which is regulated by damper s', and leads to the stack.

In operation the gas and air admitted to the supply-flues I I', as above described, pass to 95 the right or left, as directed by the reversing-valves, through the ports h into the distributing-flues E F under the centers, or nearly so of one set of regenerators. In this passage the arches H operate as deflectors and direct 100 the gas and air in opposite directions along the flues E F toward the front and rear, from

which they ascend in uniform distribution throughout the regenerating-chambers, passing the ports *c* into the flues *b*, where they are mingled and ignited at the entrance into the chambers *A*. The products of combustion pass over and heat the pots or crucibles in these chambers, and thence escape on the opposite side of the furnace from the inflow through flues *b*, chambers *B C*, flues *E, F*, 10 *I, I'*, and *S'* to the stack. When the chambers *B C* on the outflow side are sufficiently heated the valves *r²* are reversed and the inflow and outflow through the furnace is correspondingly reversed, the operation of supply and distribution being substantially the same 15 on both sides.

Heretofore in furnaces of this class it has been customary to extend the distributing flues *E F* forward to the valve-chambers and 20 pass the gas and air through them from the valve-chambers to the regenerating-chambers; or, in other words, the supply-flues opened into the ends of the distributing-flues and the gas and air were passed from one end of the regenerating-chambers, along the distributing-flues, to or toward the opposite ends of such chambers. In such construction it is difficult 25 to secure an even distribution of gas and air throughout the regenerating-chambers, and consequently of heat in the melting-chambers; and a length of furnace sufficient for four or five furnace-openings or chambers *A A'* has been found in practice to be the greatest limit which can be supplied satisfactorily 30 with such an arrangement of supply-flues. It is often very desirable to increase this length of furnace and number of furnace-openings, and by means of our improvement this may be done to the number of eight or ten openings 35 and still secure as uniform and perfect working as heretofore with four or five such openings. This advantage is secured by conducting the inflow gas and air along the flues *I I'* to the middle of the furnace, or near that 40 point, before admitting the same into the distributing-flues, and when they are so admitted they are deflected by the arches *H* in opposite directions, so that the two end halves of the regenerators are supplied with substantial uniformity. The deflecting-arches *H* perform an 45

important function in this connection in giving proper direction to the flow of gas and air in their respective distributing-flues, and to this end they may be made of any desired length, though we have found that a length about 50 equal to the width of port or opening beneath will afford very satisfactory results. Instead of arches proper, deflecting-plates may be employed, though we prefer arches of brick-work, on account of greater strength and stability. 55 The openings *h* between the supply and distributing flues may be of any desired size and form, a rectangular form being shown as most convenient of construction.

The improvement herein shown and described affords a practicable and cheap remedy for the difficulties which have heretofore placed a comparatively low limit on the size of steel-melting furnaces, and it will be found of great value, especially in large establishments, where large amounts of metal are often required for heavy work. 60

We claim herein as our invention—

1. A furnace having regenerating-chambers *B C* therein, with distributing-flues *E F* beneath and opening into such chambers, in combination with supply-flues *I I'*, opening into the distributing-flues at or near the middle of the latter, and deflecting-arches *H* over such supply-openings, substantially as set forth. 75 80

2. A steel-melting furnace having melting-chambers *A*, two sets of regenerating-chambers, *B C*, for gas and air, one set on either side of the melting-chamber, in combination with distributing-flues *E F*, having closed 85 ends—one for each regenerating-chamber—supply-flues *I I'*, opening into the distributing-flues at or near the middle of the latter, and deflecting-arches *H* over the openings between the supply and distributing flues, substantially as set forth. 90

In testimony whereof we have hereunto set our hands.

ISAAC HARPER.
SAMUEL HARPER.
